HUBERT J. TITUS, OF PATERSON, NEW JERSEY, ASSIGNOR TO FRANKLIN RAILWAY SUPPLY COMPANY, OF NEW YORK, N. Y., A CORPORATION OF DELAWARE

STEAM ENGINE

Application filed August 22, 1927. Serial No. 214,486.

This invention relates to steam engines—especially reciprocating engines—and to the means for starting them. The invention is particularly applicable to limited cut-off locomotives and it will be described as so applied.

The cut-off may be limited to a certain extent—say to about 70% maximum in full gear—without resorting to means for giving increased power at starting, but at maximum cut-offs of less than 70%, such means should be employed. An auxiliary port arrangement for admitting steam to the cylinder has been proposed for this purpose.

15 The starting arrangement, in general, should, among other things, preferably be one in which there is neither preadmission of steam while the piston is still on compression, as this would produce a negative turning movement working against the opposite cylinder of the locomotive, nor wastage of live steam to the exhaust; and in which the admission port is sufficiently large to secure effective starting effort. The arrangement should 20 also be simple and capable of application to standard engine construction, with little, if any, change.

A starting arrangement for obtaining these and other advantages is fully described in 25 copending application of Titus and Wallis, Serial No. 209,212, filed July 29, 1927.

It is one of the primary objects of the present invention to obtain such advantages in an improved manner.

30 Another object of the invention is to take more effective advantage of standard features of engine construction.

A further object is to make it possible to 35 clean the porting with ease and without the necessity of disturbing the engine parts.

Still another object is to provide a starting means which can be availed of to more effectively supply lubricant to the cylinders when drifting.

40 How the foregoing, together with such other objects and advantages as may herein-after appear are obtained, will be clear from the following description considered in connection with the accompanying drawings,

which illustrate a preferred embodiment of the invention, and in which—

Fig. 1 is a vertical longitudinal section through a typical locomotive valve chest and cylinder casting with the piston just starting a stroke to the right.

Fig. 2 is a similar view illustrating cut-off of the main port at approximately 40% of the piston stroke.

Fig. 3 is a similar view with the piston and valve farther advanced in the stroke, the auxiliary port being cut off at 70% of the stroke.

Fig. 4 is a similar view showing the valve in a position in which it has just closed the exhaust port, that is to say, the piston is at the point of compression.

Fig. 5 is a similar view showing the valve on line with the auxiliary port on the right just ready to pass steam through the auxiliary steam supply passage, which passage, however, is controlled by the piston which is still on compression.

Fig. 6 is a section taken on the line 6—6 of Fig. 4 to better illustrate the porting and passage arrangement for starting, and

Figs. 7 and 8 are partial views illustrating a modification, Fig. 8 being taken as indicated by the line 8—8 in Fig. 7.

Referring now to the drawings, it will be seen that I have illustrated a typical construction of locomotive valve chest 7, cylinder 8 and piston 9, the piston being enlarged at the bottom, as indicated at 9a. The valve chest is provided with the usual liners or bushings 7a. Steam enters the valve chest at 10 and can enter one end or the other of a cylinder through the main ports or passages 11, subject, of course, to the control of the piston valve 12 which has the enlarged ends 13 for controlling the passages 11. Exhaust takes place at the ends 14 of the valve chest. The bushings 7a are provided with the usual ports 11a communicating with the passages 11.

With the piston just starting a stroke to the right, as shown in Fig. 1, the left hand ports 11a are admitting steam to the left hand end of the cylinder, and the right hand ports 11a are open to exhaust.

The valve chest has two chambers 15 formed in the outer portion of the wall thereof, approximately in a horizontal plane cutting the longitudinal axis of the chest, which chambers communicate with the interior of the chest through the slots 15a formed in the bushings 7a (see particularly Fig. 6). These slots 15a are located at a point inside the passages 11. At the bottom of the cylinder wall 10 there are similar chambers 16 which communicate with the interior of the cylinder through the slots 16a formed in the bottom of the bushings 8a of the cylinders. A pipe 17 connects each chamber 15 with a chamber 16, and by means of the connections 17a and 17b it is possible to remove this connection. The chambers 15 and 16 and the connecting pipes constitute auxiliary steam passages for which the slots 15a are the intake ports and 20 the slots 16a the delivery ports. The slots 15a and 16a have their greatest dimension transversely of the valve chest and the cylinder, respectively, and they are of substantial area whereby steam may be delivered to the 25 cylinder in quantities sufficient to make the arrangement effective for starting.

As the piston continues to move toward the right, the valve also will move to the right as shown in Fig. 2, covering the left hand ports 11a, the cut-off being, as shown, at substantially 40% of the piston stroke. In this position live steam can enter the left hand port 15a and will flow through the respective chamber 15, pipe 17, chamber 16, 35 and port 16a into the cylinder, giving the necessary power for starting, should the locomotive have stopped in this position.

The stroke then continues as illustrated in Fig. 3, where the piston is shown at approximately 70% of its stroke, at which time the left hand ports 11a are closed, as are the ports 15a, the right hand ports 11a being still open to exhaust. Preadmission and wastage cannot occur.

45 In Fig. 4 the valve has just closed the right hand ports 11a, i. e., the piston and valve are at the point of compression. Both the auxiliary ports 15a are covered by the valve and the left hand ports 11a are covered.

50 As the piston continues on the compression portion of the stroke, the left hand ports 11a begin to open to exhaust when the valve is almost on line with the right hand auxiliary port 15a, just about ready to uncover the 55 same to steam, as shown in Fig. 5. In the position shown in Fig. 5, the right hand ports 11a and 15a are still closed and the left hand port 15a is still covered. Preadmission and wastage cannot occur.

60 On the final portion of the stroke the right hand port 15a is uncovered, but the corresponding right hand port 16a is still covered by the wide lower portion of the piston and will remain so covered when the piston is at 65 the end of its stroke, and the left hand port

15a will still be covered, so preadmission and wastage cannot occur.

On the return stroke the cycle of operations will be the same but for the opposite side of the piston. 70

It will be seen from the foregoing that there is never preadmission on the compression side of the piston or wastage of live steam. The locomotive cannot start in the wrong direction and can be started in any 75 position of the reverse lever.

By locating the ports 16a in the bottom of the cylinders, these ports are effectively covered by the piston. Advantage is taken of the fact that the piston rests on the cylinder 80 at the bottom, and, thus, when the piston is covering either one of the ports, the weight of the piston is availed of for securing effective closure. Similarly, the location of the ports 16a in the bottom takes advantage 85 of the fact that the pistons are usually made of extra width at the bottom, in consequence of which the ports are closed for a longer interval of time, making it possible to apply the auxiliary starting ports for very short 90 maximum limited cut-offs without danger of either preadmission or wastage of steam. In fact, the disposition of parts as shown will take care of a wide variation in range of maximum limited cut-offs. The particular 95 cut-off illustrated is merely typical.

The location of the ports 15a at the side also minimizes the tendency to fouling and the provision of the chambers 15 and 16 makes it very easy to clean the ports 15a and 100 the ports 16a, to which end I provide clean-out plugs 18 and 19 for the chambers 15 and 16. It will be obvious that by this arrangement it is possible to clean the ports without disturbing any of the engine parts. 105

With the provision of what is, in effect, an outside auxiliary steam passage, I can very readily connect the oil line to the pipe 17, in consequence of which oil will be fed to the cylinders for a longer period of time when 110 drifting. This may be done as roughly indicated in Fig. 6 at 20.

It will be seen that the use of the cavities 15 and 16 not only makes it possible to clean the auxiliary ports 15a and 16a, but also 115 makes it easy to line them up when rebushing either the valve chest or the cylinder. In this connection it will be seen that were a simple hole to be drilled through the wall of either the valve chest or the cylinder, it 120 would be practically impossible to line up such hole with the corresponding passage through the valve chest bushing or the cylinder bushing when a rebushing operation becomes necessary. Furthermore, the cavities 125 15 and 16 may be formed in the valve chest or cylinder bodies as shown in Figs. 1 to 6, or they may be formed as recesses or cavities 15' and 16' in the valve chest or cylinder bushings 7a and 8a, as illustrated in Figs. 7 130

and 8. In this event, it would be necessary simply to tap openings 20 and 21 in the valve chest and cylinder walls into which T fittings 22 and 23 could be screwed having removable clean-out plugs 24 and 25. The pipe 17 with its connections 17a and 17b would be coupled to the other outlets 26 and 27 of the T's.

I claim:—

1. In a steam engine, the combination of 10 a cylinder, a piston therein resting on the bottom, a valve chamber, a valve, main port connections between chamber and cylinder, and auxiliary ports of later cut off leading from the chamber to approximately the bottom of the cylinder and governed jointly by 15 the valve and the piston.

2. In a steam engine, the combination of 20 a cylinder, a piston therein resting on the bottom, a valve chamber, a valve, main port connections between chamber and cylinder, and auxiliary ports of later cut off leading from the chamber from a point in a side portion 25 of the wall of the chamber to approximately the bottom of the cylinder, and governed jointly by the valve and the piston.

3. In a steam engine, the combination of 25 a cylinder, a piston having a widened bottom portion resting on the cylinder, a valve chamber, a valve, main port connections between chamber and cylinder, and an auxiliary port connection of later cut off leading from the chamber to the cylinder at a point in the path of movement of the widened portion of the piston.

25 In testimony whereof I have hereunto signed my name.

HUBERT J. TITUS.
